Primary Examiner—Janice E. Seeger
Attorney, Agent, or Firm—Pearne, Gordon, McCoy & Granger LLP**[57] CLAIM**

The ornamental design for a pair of side tables for a glider, as shown and described.

DESCRIPTION

FIG. 1 is a perspective view of a pair of side tables for a glider, showing my new design.

FIG. 2 is a top plan view thereof.

FIG. 3 is a front elevational view thereof.

FIG. 4 is a side elevational view thereof.

FIG. 5 is a rear elevational view thereof; and,

FIG. 6 is a bottom plan view thereof.

The broken lines are for environmental purposes only and form no part of the claimed design.
